UNITED STATES PATENT OFFICE.

ROBERT C. BENDER, OF DAVENPORT, IOWA.

HUMIDIFIER.

Application filed March 17, 1927. Serial No. 176,258.

This invention relates to new and useful improvements in humidifiers and dust collectors of the type disclosed in my copending applications filed December 9, 1925, Serial No. 74,425, and April 2, 1926, Serial No. 99,317, respectively.

In this type of humidifier which is designed for use in hot air heating systems, the water container is located in a suitable casing and the latter is placed against the hot air register and preferably above the grating or grille thereof.

The objects of the present invention are to improve upon the construction of the humidifiers and dust collectors of the class described so as to insure efficient circulation of hot air through the same and bring the hot air in contact with the walls of the container, the inner surfaces of which are kept moist throughout their entire areas so as to facilitate the evaporation of water and insure proper degree of humidity.

Further objects of the invention are to provide a device of the class described in which the circulation of hot air is greatly increased and the air upon being properly conditioned or humidified is caused to pass through a suitable dust collector or screen which separates the dust from the air passing therethrough.

Still further objects of the invention are to provide a novel form of water container by means of which the areas of the air passages are considerably increased and the evaporation of water is greatly facilitated.

Additional objects of the invention are to provide walls of the water container with absorbent lining which lining is kept moist above the water level by capillary action so that the evaporation of water readily takes place in said humidifier.

With these and other objects in view, my invention consists in certain novel features of construction and arrangement of parts, hereinafter more fully described and claimed, and illustrated in the accompanying drawings, in which—

Figure 1 is a front elevational view of the humidifier attached in position on the grating and having portions broken away to more clearly illustrate the construction thereof.

Figure 2 is an enlarged vertical cross section taken transversely through the humidifier.

Figure 3 is an end elevational view, partly

broken away, of the lower portion of the humidifier and the parts associated therewith.

Figure 4 is a top plan view of the humidifier with the cover thereof removed.

Figure 5 is a perspective detail view of one of the absorbent lining members.

Figure 6 is an enlarged horizontal cross section taken through one end of same.

Figure 7 is a fragmental detail view of the humidifier and showing a modified form of dust deflector or apron.

Figure 8 is a vertical section taken on line 8—8 of Figure 7.

Referring by numerals to the accompanying drawings, 10 indicates a wall register of a hot air heating system having a grating or grille 11 on the upper portion of which rests the lower end of casing 12. This casing comprises a rear wall 14, end walls 15, and a front wall 16, and is open at top and bottom as indicated at 17 and 18, respectively.

The front wall 16 is preferably inclined upwardly and outwardly so that the cross sectional area of the casing increases upwardly. The upper end of the casing is closed by a removable cover 19 provided in its front and top walls with apertures 20 through 25 which the air is discharged from the humidifier. The lower portion of front wall 16 is provided with an opening extending the full width of the casing as indicated at 16^a, while the upper portion of said front wall 16 is formed imperforate.

A deflector or apron 21 extends downwardly and forwardly from the front wall 16 a suitable distance below said casing and deflects the air discharged through the register 10 into said casing through opening 16^a. This deflector is of greater width than the width of the casing, thereby forming side portions 21^a which extend rearwardly on each side of casing 12. Each end wall 15 is provided with horizontally disposed outwardly projecting portions 23 and 24, respectively, one of which 23 is located near the front wall 16 while the other end 24 is located near the rear wall 14.

Projection 23 is disposed below the horizontal plane of projection 24 and when the deflector 21 is in position, projections 23 engage the underside of the side portions 21^a and form a rest therefor, while projections 24 engage the upper side of side portions 21^a as shown in Figure 3. Said portions 21^a ter-

minate in upwardly projecting flanges 21^b which project upwardly and are disposed rearwardly of projections 24 and form stops which prevent disengagement of the deflector 21 from its position on the casing.

Deflector 21 is preferably provided with a downwardly presented marginal flange 21^c. Extending from wall 16 immediately above opening 16^a is a horizontally disposed flange 25 which forms overlapping engagement with horizontally disposed portion 21^d of deflector 21, and thereby assists in supporting the deflector in position and seals the joint between the casing and said deflector, thereby preventing escape of air therethrough.

A water container 26 is removably arranged within casing 12 and is spaced from the walls thereof so as to provide suitable air passageways 27. In order to increase the surfaces of the container coming in contact with the hot air, said container is provided with a centrally disposed tubular portion or flue 28 which extends the full height of the container and is open at top and bottom to allow the passage of hot air therethrough. The container is supported in position in casing 12 by means of a pair of L-shaped brackets 29 the vertical portions of which are secured to the rear wall 14 as indicated at 30 while the horizontal portions thereof extend transversely of the open bottom of the casing and form supports for the container as shown in Figure 2.

The lower edge of rear wall 14 is preferably notched for the reception of horizontal portions 29^a of brackets 29 so that said portions are disposed flush with the lower edge of said rear wall 14 and the rear wall 14 is formed with offsets and recesses 14^a to bring the vertical portions 29^b flush with said rear wall.

The inner faces of the walls of the water container are preferably lined with absorbent material as indicated at 31, which material is kept saturated with water contained in the container so that the evaporation of the water is greatly facilitated. Portion 28 is provided with a tubular absorbent portion 31^a which is slipped thereover while the walls of the container are provided with absorbent material members 32 which are carried by suitable frames 33. The latter terminate in hook portions 34 by means of which said members can be removably supported within the container.

Cover 19 is provided with inwardly projecting horizontally disposed lugs 35 on which is supported a wire frame 36 carrying a screen preferably of fabric 37 which serves to catch the dust and separate it from the air. Frame 36 and screen 37 preferably are co-extensive with the cross sectional area of the cover so that the hot air properly humidified is caused to pass through the screen be-

fore entering chamber 38 formed in the cover 19.

Screen 37 is of proper mesh to allow filtration of air therethrough without materially affecting the circulation of air. The air in passing through the screen is rid of dust particles which are arrested in their movement by the screen. Thus the hot air issuing from the apertures in the cover is of proper humidity and is purified so that it will not bring dust into the room. Screen 37 is removable so that said screen can be replaced at stated intervals.

The device is supported in position by suitable supporting means 39 comprising side bars or arms 40 attachable at their upper ends to the side walls 15 by fastening devices 41 and having their lower ends secured to upturned ends 42 of a horizontal bar 43 by attaching means 44. One end of each bar 40 is slotted as indicated at 45 to permit adjustment of said bars longitudinally relative to the parts with which they are associated. The horizontally disposed bar 43 is secured to the grille or grating 11 by screws 46 which clamp the grille between bar 43 and short pieces 47, which latter are arranged on the inner side of the grille. Horizontally disposed slots 48 are provided in bar 43 for receiving screws 46 so that the whole device may be shifted in a horizontal plane relative to the grille. In this manner, a simple support is provided for the device and said device has a wide range of adjustment, permitting the use of the device in conjunction with grilles of various designs.

In the modified form shown in Figures 7 and 8 a deflector 49 is provided with a rear extension 50 which is vertically disposed and adapted to be inserted behind the register 10, thereby maintaining the device in position. The portions 49^a of the deflector are engaged by brackets 51 which are removably secured on the inside of end walls 15^a and have horizontal portions 52 projecting outwardly through openings 53 and engaging the underside of said side portions 49^a.

My improved humidifier and dust collector is constructed so as to allow maximum circulation of hot air therethrough, whereby the water container is heated efficiently to effect ready evaporation of water and it is obvious that the more heat passes through the container the more humidity is produced and a greater percentage of dust is collected by the dust screen. The absorbent lining provides a greatly increased area of moist surfaces as the entire inner surfaces of the container walls are kept moist regardless of the level of the water. As long as the water is present in the container the absorbent lining will be kept moist by capillary action.

While I have shown the absorbent lining

covering all the walls of the container, generally only the lining covering the central flue will be necessary to provide the desired humidity.

5. A humidifier and dust collector of my improved construction can be readily attached and detached from the register, does not occupy very much space and presents a neat appearance.

10. I claim:

1. A humidifier and dust collector for hot air heating systems comprising a casing open at top and bottom and adapted to be supported by the wall register, a water container

15. removable arranged in said casing in spaced relation with the walls thereof, a lateral extension projecting from the front wall of said casing, there being an opening formed in said wall below said extension

20. whereby hot air discharged by the register is deflected by said extension through said opening into said casing, a perforate cover for closing the top of said casing, and absorbent material arranged in said container and kept saturated with the water contained therein.

25. 2. A humidifier and dust collector for hot air heating systems comprising a casing open at top and bottom and adapted to be supported by the upper portion of a wall register, a water container arranged in said casing in spaced relation with the walls thereof, a lining of absorbent material arranged on the inner faces of said container

30. and kept saturated with water by capillary action, a cover removably closing the upper end of said casing and provided in its top and front walls with apertures, and a dust screen removably arranged in said cover

35. 40. and coextensive with the cross sectional area thereof for extracting dust from the air passing from said casing into said cover.

3. A humidifier and dust collector for hot air heating systems comprising a casing open at top and bottom and adapted to be supported by the upper portion of a wall register, a water container arranged in said casing in spaced relation with the walls thereof, a lining of absorbent material arranged on the inner faces of said container

45. and kept saturated with water by capillary action, a cover removably closing the upper end of said casing and provided in its top and front walls with apertures, a dust

50. screen removably arranged in said cover and coextensive with the cross sectional area thereof for extracting dust from the air passing from said casing into said cover, and a deflector extending forwardly and

55. 60. downwardly from said casing for deflecting air thereinto through an opening formed in the front wall of said casing.

4. A humidifier and dust collector for hot air heating systems comprising a casing open at top and bottom, supports attach-

able to said casing and adapted to be secured to the grating of a hot air wall register, a water container arranged in said casing in spaced relation with the walls thereof, a lining of absorbent material removable arranged on the inner faces of the walls of said container and kept moist by capillary action, and a deflector extending forwardly and downwardly from said casing in front of said wall register for deflecting the air into said casing, the front wall of the latter being imperforate above said reflector and provided with a large opening below said deflector for admitting air into said casing.

5. A humidifier and dust collector for hot air heating systems comprising in combination a casing open at top and bottom and adapted to rest on the top portion of a wall register, a water container removable arranged in said casing in spaced relation with the walls thereof, a removable cover for closing the upper end of said casing, said cover being provided in its top and front walls with apertures, and a deflector plate 85 extending from the front wall of said casing and provided with side extensions adapted to detachably engage the side walls of said casing for supporting said plate in position thereon, the front wall of said casing being imperforate above said deflector and being cut away below said plate to form an opening for admitting air thereinto.

6. A humidifier and dust collector for hot air heating systems comprising in combination a casing open at top and bottom, and having an obliquely disposed front wall whereby the top of said container is of greater cross sectional area than the bottom thereof, supports for mounting said casing on a wall register of said heating system, a water container arranged in said casing in spaced relation with the walls thereof, a lining of absorbent material arranged on the inner faces of the walls of said container for maintaining the walls thereof moist regardless of the level of the water contained therein, and a cover for the open top of said casing, said cover being provided with air discharge apertures.

7. A humidifier and dust collector for hot air heating systems comprising in combination a casing open at top and bottom, and having an obliquely disposed front wall whereby the top of said container is of greater cross sectional area than the bottom thereof, supports for mounting said casing on a wall register of said heating system, a water container arranged in said casing in spaced relation with the walls thereof, a lining of absorbent material arranged on the inner faces of the walls of said container for maintaining the walls thereof moist regardless of the level of the water contained therein, a cover for the open end of said

casing, said cover being provided with air discharge apertures, and a dust screen removably arranged in said cover and coextensive with the cross sectional area thereof, of whereby the air passing from said casing into said cover is caused to traverse said dust screen and the dust is arrested thereby.

8. A humidifier and dust collector for hot air heating systems comprising a casing 19 open at top and bottom, supports for mounting said casing on top of a wall register of said heating system, a water container removably arranged in said casing in spaced relation with the walls thereof, said container being provided with a centrally disposed flue extending the full height of said container, a removable cover for the top of said casing, said cover being provided with suitable air openings, and brackets secured 20 to the rear wall of said casing and extending transversely thereinto to form supports for said container.

9. A humidifier and dust collector for hot air heating systems comprising a casing 25 open at top and bottom, supports for mounting said casing on the top portion of a wall register, a water container arranged in said casing in spaced relation with the walls thereof to provide air passages in said casing, said casing being provided in the lower portion of its front wall with an elongated horizontally disposed opening, a horizontally and forwardly disposed flange projecting from said wall immediately above 30 said opening, and a deflector removably secured to said casing and engaging said flange and extending downwardly and forwardly from said casing in front of said register for deflecting the air through said 35 opening into said casing.

10. In a humidifier and dust collector for hot air hot air heating systems, in combination with a casing adapted to be attached to a wall register and having an open bottom, 40 of a water container removably arranged in said casing, and provided with a central air flue open at top and bottom and a plurality of sheets of absorbent material disposed adjacent to the inner faces of said container 45 and kept moist by capillary action and a deflector detachably secured to said casing and extending obliquely from the front wall thereof for deflecting the air through an opening formed in the front wall of said casing thereinto and into the central flue of said water container.

11. In a device of the class described, the combination of a casing attachable to a wall register and open at top and bottom, a water container removably arranged in said casing, a tubular air flue extending from the bottom to the top of said container to form a hot air passage within said container and a removable cover for the top of said casing, said cover being provided with suitable air

openings and being spaced from the top of said water container to form a chamber wherein the hot air and the water vapors can mix before being discharged from said casing.

12. In a device of the class described, the combination of a casing attachable to a wall register and open at top and bottom, of a water container removably arranged in said casing, a tubular air flue arranged centrally and vertically in said container in spaced relation with the side walls thereof and extending from the bottom to the top of said container to form a hot air passage within said container, a tubular covering of absorbent material removably arranged on said flue and kept moist by the water in said container and a removable cover for the top of said casing, said cover being provided with suitable air openings and being spaced from the top of said water container to form a chamber wherein the hot air and the water vapors can mix before being discharged from said casing.

13. In a device of the class described, the combination of a casing open at top and bottom, a perforate cover removably arranged on the top of said casing, a water container removably arranged in said casing in spaced relation with the walls thereof, a flue arranged in said container, absorbent material in said container for maintaining the walls of said container moist by capillary action, arms adjustably secured to the end walls of said casing, and means adapted to be fixed to the grille of a hot air wall register and secured to said arms for supporting said casing in position.

14. A humidifier and dust collector comprising in combination a casing open at top and bottom, said casing being provided with an obliquely disposed front wall having an elongated horizontally disposed opening formed therein near the bottom thereof for admitting air into said casing, a perforate cover removably arranged on the top of said casing, a water container removably arranged in said casing in spaced relation with the walls thereof, a tubular flue disposed vertically and centrally in said container and open at top and bottom, a covering of absorbent material removably arranged on the wall of said flue and kept saturated with the water in said container, thereby facilitating the evaporation thereof, a plate extension extending forwardly and downwardly from the front wall of said casing for deflecting the air from the air register into said casing and through said flue by means of the opening formed in the front wall of said casing, and means for supporting said humidifier and dust collector in position.

In testimony whereof, I hereunto affix my signature this 11th day of March, 1927.

ROBERT C. BENDER,
